METHOD OF LOWERING ICE-BUCKLED
COLD ROOM FLOORS

Alonzo W. Ruff, York, Pa., assignor to V. C. Patterson & Associates, Inc., York, Pa., a corporation of Pennsylvania

Application January 12, 1950, Serial No. 138,112

6 Claims. (Cl. 61—36)

1

This invention relates to refrigerated cold storage or freezing rooms having their floors built directly on the ground. More particularly this invention pertains to a method of lowering such floors which have buckled upwardly, due to the formation of ice in the subjacent earth, without entirely tearing up and replacing the floor.

The floors of cold storage rooms which are built directly on the ground ordinarily consist of upper and lower layers of concrete separated by a layer of thermal insulation material, usually cork. Even though such floor is insulated, there is a transfer of heat therethrough from the ground immediately adjacent the underside of the lower concrete slab into the room. The earth, which is usually a fairly good heat insulator, resists the flow of heat from lower elevations to replace this heat loss. Hence, the earth under the floor gradually chills and, in time, reaches freezing temperature.

Once freezing temperature is reached moisture in the earth begins to freeze and form ice. Such formation is effected in strata-like layers separated by thin layers of earth. Experience indicates that such ice, once formed, does not melt unless the floor is warmed up for some time. These ice accumulations have a highly destructive effect because of the expansion which takes place during their formation. It often takes several years for enough ice to accumulate to cause visible damage, but experience has proved that the formation of such ice creates a force that raises and eventually buckles or ruptures the floor. This is particularly true of large rooms. Cases have been observed where the floors buckled up to 12 inches, even though a few inches is usually serious enough to put a cold room out of service. In a few known instances the entire building structure was shattered by such ice formation.

Preventive measures are known. Such measures include the casting of warming pipes in the lower floor slab, and constructing the floor with an air space between the floor and the subjacent earth. These preventive measures, while effective, can be incorporated only on new construction and cannot easily be employed to correct the situation once it develops. Prior to this invention the only known method of coping with an ice-buckled floor was to tear up the entire floor, thus sufficiently damaging the expensive cork insulation to render it unfit for further use, and to re-lay the entire floor. Such procedure is a time consuming and costly operation, sometimes amounting to as high as \$4.00 per square foot of floor area.

Accordingly, it is an object of this invention to provide a simple and inexpensive method, involving a minimum of time and labor, for lowering and settling the earth-laid concrete floor of

2

a refrigerated room that has buckled upwardly due to the accumulation of ice in the subjacent earth.

It is a further object of this invention to provide such a method that will also prevent the further accumulation of ice.

Other objects and advantages of the invention will be evident from the following description and accompanying drawing in which:

Figure 1 is a fragmentary view, in vertical section, of a refrigerated room having a ground-laid floor that has been buckled by the formation of ice in the subjacent earth.

Figure 2 is an enlarged fragmentary view of a portion of Figure 1 illustrating the method of lowering the buckled floor in accordance with this invention.

Figure 3 is a view corresponding to Figure 2 illustrating the lowered floor upon completion of the method of this invention.

Referring now to Figure 1, there is shown a portion of refrigerated room 10 having a side wall 11 resting upon a concrete foundation 12 and provided with interior insulation 13. The wall 11 may be of any suitable construction material, such as concrete, wood, brick, cinder block, etc. The insulation 13 preferably is cork, although other appropriate thermal insulating material can be used.

The floor of the room, which is laid directly upon the ground 14, preferably consists of upper and lower slabs of concrete 15 and 16, respectively, separated by a layer of thermal insulation 17, preferably cork. The lower slab 16 serves as a foundation for both the insulation 17 and the upper slab 15, which latter is the actual floor of the room 10. Continuous low temperatures in the room 10 have resulted in the formation of layers of ice 18 in the earth 14, beneath the floor.

The expansive forces created by the gradual accumulation of the layers of ice have slowly raised and finally effected buckling of the floor as indicated generally at 19. Hence, this buckled area of the floor is no longer useful. Additionally, the break 20 in the cork insulation permits a more rapid transfer of heat from the subjacent earth 14 to the room 10, so that ice accumulation is accelerated with consequent increase in the rate of damage to the floor.

In order to lower the buckled area of the floor in accordance with this invention, a pit or hole 21 is sunk through the critical point in the floor and into the frozen ground 14 therebeneath, as shown in Figure 2. This pit 21 is of a size sufficient to enable apparatus, subsequently described, to be easily manipulated therein. A pit 3 to 4 feet square and deep enough to extend 3 or 4 feet below the normal level of the lower slab 16 is usually adequate.

The next step consists of forcing or driving a

plurality of sectional conduits horizontally outwardly through the side walls of the pit 21 into the frozen ground beneath the floor. The conduits are arranged to radiate from the pit in order to cover the entire affected area. Each conduit consists of a pointed nose section 22 and a plurality of additional sections 23 adapted to be threadedly or otherwise suitably coupled together. After the nose section 22 has been driven into the earth the next section 23 is coupled on and the two sections driven further into the earth. Additional sections 23 are successively connected to the conduit and the latter driven farther into the earth until the nose section 22 substantially reaches the periphery of the iced area.

The purpose of these conduits is to carry electric heating cables 24. One end of each cable is secured in the nose section 22 and the cable strung through the remaining sections 23 of each conduit before the latter are successively joined together.

The conduits may be driven or forced into the frozen earth by any suitable means. One practical means is a hydraulic jack (the cylinder of which is shown at 25), preferably of ten tons or larger rating, which is appropriately blocked, as at 26, and shored, as at 21, in operating position in the pit 21. In order to prevent damage to the heating cable during the operation of the jack cylinder 25 a pressure head 28, which is slotted, as at 29, to pass the cable 24, is used between the conduit and the jack plunger 30. The jack hydraulic pump (not shown) may be made as a unit with the cylinder 25 or be a separate mechanism adapted to be positioned out of the pit and connected to the cylinder by appropriate hydraulic lines.

If the ground is frozen so hard that it is impracticable to force or drive the conduits thereinto, lateral holes may be bored or drilled in the side walls of the pit by means of suitable earth drilling apparatus (not shown). The conduits may then be inserted in place in such holes with little difficulty.

After all the conduits have been forced into place, the cables 24 are connected with a suitable source of electric power (not shown) by a power connection (not shown) that leads out of the pit. The pit may then be filled up with earth to about the level of the conduits (as shown in Fig. 3). Thermal insulating material, such as rock wool blankets 31, is used to fill the remainder of the pit. Current is then supplied to the cables 24 to warm the conduits and melt the layers of ice 18. As the ice melts, the floor will gradually lower under its own weight. A period of about one month, or even longer, may be necessary to completely melt the ice and dry the earth sufficiently to permit the floor to settle back to its original position shown in Figure 3. Because of the pit insulation 31, however, the room may be placed in service during such period.

After the floor has settled completely, an angle frame 32 may be fitted in the mouth of the pit to receive a wooden pit cover 33. The pit insulation 31 is left in place as a replacement for discarded cork insulation. Any large cracks remaining in the floor after it has settled completely preferably are sealed with a suitable caulking compound.

To prevent a recurrence of ice formation when the room is back in service, current is reapplied as needed to the heating cables. A suitable thermostatic control for such current is the most convenient means of preventing the temperature

of the subjacent earth from again lowering to freezing. An earth temperature of the order of 40° F. is usually practical from the standpoint of power consumption.

Preferably the repair of buckled floors by this method is initiated before the floors have been damaged to the extent that lowering will not be practical, for example, if the floor has been broken into many small pieces. It is obvious that this method can be used at more than one location in the floor. Several pits and associated conduit arrangements may be necessary, for example, to completely lower the floor of a large room which has buckled at several places.

Modifications of this invention will occur to one skilled in the art. Therefore, this invention embraces all embodiments which come within the spirit and scope of the following claims.

I claim:

1. The method of lowering the earth-laid floor of a refrigerated room, which floor has been buckled upwardly by the formation of ice accumulations in the subjacent earth, the steps comprising: sinking a pit into the earth adjacent the buckled area of the floor; disposing heating conduits substantially horizontally through at least one sidewall of said pit into the iced earth beneath said buckled area; and supplying heat to said conduits for a period sufficient to melt the ice accumulations and dry the earth beneath said buckled area to thereby permit the buckled floor to settle back to normal position under its own weight.

2. The method defined in claim 1 including the additional step of preventing the reformation of ice accumulations, once they have melted and after the room is back in service, by continuing to supply heat to the heating conduits sufficiently to maintain an above-freezing temperature of the subjacent earth.

3. The method defined in claim 1 in which heat is supplied to the conduits electrically and locally.

4. The method defined in claim 1 in which the disposing step is accomplished by forcing the heating conduits into the iced earth.

5. The method defined in claim 1 in which the disposing step is accomplished by boring lateral holes into the sidewall of the pit and inserting heating conduits into said holes.

6. The method of lowering the earth-laid concrete floor of a refrigerated room, which floor has been buckled upwardly by the formation of ice accumulations in the subjacent earth, the steps comprising: excavating a pit, adjacent the buckled floor area, through the floor and into the subjacent frozen earth; disposing elongated electrical heater means substantially horizontally through the sidewalls of said pit into the iced earth; supplying electric current to said heater means for a period sufficient to melt the ice accumulations and dry the earth beneath said buckled area to thereby permit the buckled floor to settle back to normal position under its own weight; filling said pit with thermal insulating material in at least the upper portion thereof; and covering said pit with rigid material.
